Primary Examiner — Cynthia Ramirez*Assistant Examiner* — Llorellys Martinez-Rivera(57) **CLAIM**

I claim the ornamental design for an electronic component necklace, as shown and described.

DESCRIPTION

FIG. 1 is a front elevation view of the electronic component necklace showing my new design.

FIG. 2 is a rear elevation view thereof.

FIG. 3 is a side elevation view thereof.

FIG. 4 is a top plan view thereof; and,

FIG. 5 is a bottom plan view thereof.
